UNITED STATES PATENT OFFICE

FRANK L. GORMLEY, OF CHICAGO, ILLINOIS, ASSIGNOR TO THE BUDA COMPANY, OF HARVEY, ILLINOIS, A CORPORATION OF ILLINOIS

RATCHET JACK

Application filed March 31, 1928. Serial No. 266,309.

This invention relates to ratchet jacks and particularly to jacks of this character in which the load is raised by means of a lever carrying a pawl which engages a rack movable endwise, the object of the invention being the provision of means which will prevent any accidental lowering of the rack while sustaining a load.

This object is attained by the mechanism illustrated in the accompanying drawings.

For the purpose of illustrating the invention, one preferred form thereof is illustrated in the drawings, this form having been found to give satisfactory and reliable results, although it is to be understood that the various instrumentalities of which the invention consists can be variously arranged and organized, and the invention is not limited to the precise arrangement and organization of these instrumentalities as herein shown and described except as required by the scope of the appended claims.

In the drawings:

Figure 1 represents a vertical section of a lifting jack embodying the principles of the present invention, the cutting plane being on line 1, 1, on Fig. 2.

Figure 2 represents a transverse section of same on line 2, 2, on Fig. 1.

Figure 3 represents a partial transverse section showing the lifting and holding pawls interlocked.

Figure 4 represents an elevation of the lifting pawl, and

Figure 5 represents an elevation of the holding pawl.

Similar characters indicate like parts throughout the several figures of the drawings.

In the drawings, 10 is a hollow casing extending upwardly from a base 11, the upper end of this casing having handle 12 projecting therefrom by which the jack may be carried from place to place.

The casing walls have various openings therein through which the various movable elements of the jack may be assembled.

This casing 10 is provided at the top with a square bearing 13 through which extends the

ram or rack 14 having on one side thereof a plurality of teeth 15.

This ram or rack 14 has secured to its upper end a supporting head 16 and at its lower end has projecting therefrom another supporting member 17. Either the head 16 or projection 17 may be used to support a load.

The projecting member 17 extends through a slot 18 in one side wall 19 of the casing 10.

The ram 14 contacts with the inner face of this wall 19 as it reciprocates endwise therein, the teeth 15 being free from contact with the opposite wall 20.

The ram 14 may be inserted through the opening 21 in the base 11 and after such insertion the head 16 is secured thereto by means of the pin 22.

The side walls of the casing 10 have openings therein to receive the oppositely disposed cup-shaped members 23 held in the side walls 70 of casing 10 by set screws 23a.

Disposed within these cup-shaped members 23 are trunnions 24 projecting from the opposite sides of a lever 25 adapted to receive an actuating lever, not shown.

The inner faces of the side walls of casing 10 are cut away at 24a forming grooves through which the trunnions 24 may be moved into position so that the cup-shaped members 23 may be disposed over the ends thereof and form bearings therefor.

The inner end of this lever 25 is provided with a semi-cylindrical seat 26 to receive the cylindrical end 27 of a lifting pawl 28 and said inner end is cut away at one side thereof as at 26a to permit the insertion of the pawl 28 from one side of the lever 25 with its cylindrical end 27 disposed in its seat 26.

The seat 26 on the opposite side of the lever 25 is cylindrical with no slot 26a extending therefrom.

The pawl 28 is provided with a plurality of teeth 29 adapted to engage the teeth 15 of the ram or rack 14.

Near the upper end of the casing 10 is disposed another pair of cup-shaped members 30 to receive the trunnions 31 formed upon a holding pawl 32, the lower end of which has formed thereon a plurality of teeth 33 adapted to engage the teeth 15 of the ram or rack 14.

The inner faces of the side walls of casing 10 are cut away at 31 α to permit the proper positioning of the trunnions 31 after which the cup-shaped members are placed over the 5 ends of said trunnions 31 and form bearings therefor.

The cup-shaped members 30 are held in position by the set screws 30 α .

The cup-shaped members 28, 30 are each 10 provided with a threaded opening in which is disposed a closure 34 which may be removed in order to admit lubricant to the trunnions 24, 31.

The holding pawl 32 is provided with an 15 extension 35 having in the lower end thereof a notch 36 adapted to receive the upper end of the lifting pawl 28 under certain conditions which will be hereinafter described.

The lifting pawl 28 has on one side thereof 20 an extension 37 by which the said pawl may be moved about its pivot to bring the upper end of said pawl into the notch 36.

This pawl 28 is also provided with side extensions 38, 38 α which coact with the side 25 faces of the ram or rack 14 to prevent displacement of the pawl 28 under all conditions.

The upper end of the holding pawl 32 is 30 bifurcated and straddles the rack 14 thus preventing any side movement of the pawl.

To one side wall of the casing 10 is secured a headed stud 39 about which is coiled a spring 40.

One end of this spring 40 coacts with the 35 side extension 38 α while the opposite end of the said spring coacts with a headed projection 41 on one side of the holding pawl 32, the tension of said spring being such as to cause the ends thereof to spring away from 40 each other.

The same spring, therefore, retains under 45 normal conditions the teeth of both the lifting pawl 28 and the holding pawl 32 in engagement with the teeth 15 of the ram or rack 14.

The lever 25 is provided with a downward projection 42 which is adapted to engage a shoulder 43 on the casing 10 to limit the downward movement of said lever.

When the lever 25 is moved downwardly 50 the lifting pawl will raise the ram or rack 14, the holding pawl 32 being forced outwardly from engagement with the rack teeth 15 against the tension of the spring 40, while 55 the rack teeth 15 are passing the teeth 33 of holding pawl 32. As soon as the lever 25 is moved in the opposite direction the spring 40 will force the holding pawl teeth 33 into engagement with the rack teeth 15 and retain 60 the rack 14 in its elevated position.

This is of considerable importance as with 65 this type of jack there has always been a tendency for the holding and lifting pawl to fly out of contact with the rack teeth and allow 70 said rack and the load supported thereby to

accidentally lower and thus cause serious accidents.

By providing a single spring 40 in the manner shown and described both of the pawls 28, 31 are retained in engagement with the rack 70 teeth 15 at all times except when the load is being lowered.

When it is desired to lower the rack 14 the lifting pawl 28 is moved away from the rack 14 so that its upper end is positioned within 75 the notch 36 of the holding pawl 32.

When this engagement between the pawls 28 and 32 has been effected a downward movement of the lever 25 will force the holding pawl 32 about its pivot 31 and move the teeth 80 of said holding pawl 32 out of engagement with the rack teeth 15.

The rack 14 will then be permitted to drop as soon as the teeth of the holding pawl 32 85 have disengaged the teeth on the rack 14.

After the load has been lowered the lever may be raised and in so doing the upper end of the pawl 28 will be removed from the notch 36 and the holding pawl 32 and the spring 40 will then force both of the pawls 28, 31 again 90 into engagement with the rack teeth ready for another operation.

While the load is being supported either upon the head 16 or the projection 17 the 95 spring 40 will retain the teeth of both of the pawls 28, 31 in engagement with the rack teeth 15.

This gives a double provision for safety as if anything should happen to one pawl the other pawl would still remain in engagement 100 and prevent any accidental lowering of the load.

Another advantage of the device is that with both the lifting pawl 28 and the holding pawl 32 held in engagement by means of the 105 spring 40, it is possible to operate the jack at any angle as neither pawl can come out of engagement with the rack teeth 15 owing to the action of the spring 40 thereon.

It is believed that the operation and many 110 advantages of the invention will be understood without further description.

Having thus described my invention, I 115 claim:

1. In a lifting jack, a supporting casing; a 115 rack movable endwise therein; a pivoted lever; a lifting pawl carried thereby; a holding pawl pivoted to said casing and provided with a shoulder adapted to be engaged by the end of said lifting pawl; and a spring on said casing the ends of which are adapted to spring away from each other and simultaneously 120 force both pawls into engagement with the teeth of said rack during the separation of the ends of said spring.

2. In a lifting jack, a supporting casing; a 125 rack movable endwise therein; a pivoted lever; a lifting pawl carried thereby; a holding pawl pivoted to said casing and provided with a shoulder adapted to be engaged by the 130

end of said lifting pawl; a laterally extending handle integral with said lifting pawl by which it may be moved about its pivot; and a spring on said casing for forcing both pawls into engagement with the teeth of said rack.

3. In a lifting jack including a rack movable endwise and provided with teeth; a pivoted lifting pawl coacting with said teeth and movable to impart end movement to the rack; a pivoted holding pawl also coacting with said teeth and having a notch to receive the end of the lifting pawl when disengaged from the rack teeth; and a single spring the ends of which are adapted to spring away from each other to force both pawls into engagement with the rack teeth when said pawls have been disengaged from each other.

4. In a lifting jack including a rack movable endwise and provided with teeth; a pivoted lifting pawl coacting with said teeth; a holding pawl also coacting with said teeth; manually actuated means whereby the lifting pawl may be disengaged from the rack teeth and locked to the holding pawl; means for moving the lifting pawl while thus locked and causing the holding pawl to be disengaged from said teeth; and a single spring the ends of which are adapted to spring away from each other and simultaneously force both pawls into engagement with the rack teeth as soon as released.

5. In a lifting jack, a supporting casing; a rack movable endwise therein; a pivoted lever; a lifting pawl carried thereby; a holding pawl having oppositely disposed trunnions; cup-shaped members disposed in the side walls of said casing to receive said trunnions and form bearings therefor; and a spring on said casing opposite said rack and the ends of which are adapted to spring apart and normally retain both pawls in engagement with the teeth of said rack.

6. In a lifting jack, a supporting casing; a rack movable endwise therein and provided with teeth; a pivoted lifting pawl coacting with said teeth; means for imparting movement to said pawl while engaged with the rack to effect end movement of said rack; a pivoted holding pawl also coacting with said teeth; projections on said pawls; a headed stud within said casing opposite said rack; and a single spring coiled about said stud and having outwardly extending ends adapted to spring apart and coact with lateral projections on said pawls thereby retaining both pawls in engagement with the rack teeth under normal conditions but permitting each pawl to move independently of the other about its pivot.

60 7. In a lifting jack, a supporting casing; a rack movable endwise therein; a pivoted lever; a lifting pawl carried thereby; a laterally extending lug on said pawl; and a spring on said casing engaging said lug and adapted to force said pawl into engagement

with the teeth of said rack, said spring being secured to the casing opposite a side wall of said rack.

8. In a lifting jack including a rack movable endwise and provided with teeth; a lifting pawl adapted to coact with said rack teeth; a holding pawl also adapted to coact with said rack teeth; a single spring the ends of which are adapted to spring apart and simultaneously retain both pawls under normal conditions in engagement with the rack teeth; manually actuated means whereby said lifting pawl may be moved independently of the holding pawl; and means for holding said pawls in engagement with each other under certain conditions.

Signed by me at Harvey, Illinois, this 28th day of March, 1928.
